UNITED STATES PATENT OFFICE.

WILLIAM C. HOMAN, OF MERIDEN, CONNECTICUT, ASSIGNOR TO EDWARD MILLER & COMPANY, OF MERIDEN, CONNECTICUT, A CORPORATION OF CONNECTICUT.

GLOBE AND SHADE HOLDEER.

1,029,298.

Specification of Letters Patent. Patented June 11, 1912.

Application filed March 15, 1912. Serial No. 683,976.

To all whom it may concern:

Be it known that I, WILLIAM C. HOMAN, a citizen of the United States, residing at Meriden, county of New Haven, State of Connecticut, have invented certain new and useful Improvements in Globe and Shade Holders, of which the following is a full, clear, and exact description.

My invention relates to an improved shade 10 and globe holder particularly useful in connection with so-called inverted incandescent mantle burners.

The object of the invention is to provide a simple and effective globe holding device 15 which may be cheaply produced and easily operated.

In the drawings Figure 1 is a view of the under side of the burner tube with the globe support attached thereto. Fig. 2 is a front 20 elevation of the same parts with the globe in place. Figs. 3 and 4 are detail views.

1 represents the supporting fixture or burner tube carrying the globe holder. The globe holder comprises the main body portion 2, which is attached to the fixture 1 in any suitable manner. At the edge of the main body 2 is a depending annular flange 3, having preferably an internally channeled portion extending entirely around the 30 flange.

4 represents a globe which may be of any suitable form and which is provided with the flanged neck 5.

The holding device comprises a one-piece 35 spring wire which is of peculiar form. As shown, the wire is bent in the middle to provide a U-shaped portion 6, which projects through a slot 7 in the flange 3; said slot having a central restricted portion or hour-glass contraction to hold the wire in place. Projecting in opposite directions from the U-shaped part of the wire retainer are arms 40 8-9, each of which is of greater length than a semi-circle, so that the two ends of the wire will overlap. The extreme ends of the wire are offset, as shown, to provide operating handles 10-11.

12 is a slot in the flange 3 opposite to the slot 7 having the hour-glass contraction. 50 The slot 12 is widest at its middle portion, the two ends being slightly out of line, as shown. By this form, the two handle ends 10-11 of the globe gripping wire may be pressed together by the thumb and forefinger, so that the two sides 8-9 will be

expanded laterally into the channel around the inner side of the flange 3, thus affording sufficient clearness to permit the flange 5 of the globe to be inserted to a position above the side arms 8-9. When the handle ends 60 10-11 are released, the wire holder contracts, bringing the side arms 8-9 into gripping contact with the globe 4 beneath the flange 5; so as to securely hold the latter in place.

It is apparent at once that the device is capable of being very cheaply made, comprising only two parts, and likewise may be very easily assembled, since the edges of the slot 7 may be first bent open to permit the 70 U-shaped part of the wire retainer to be slipped in place, after which said edges may be bent into line to contract the space and retain the wire in place. In assembling, of course the handle ends 10-11 would first be 75 inserted or passed through the slot 12. When fully assembled, the wire retainer is held in place by the contracted edges of the hour-glass passage 7, while the ring is supported at opposite sides by that part of the 80 flange 3 which constitutes the lower edge of each of the slots. The hour-glass passage 7 serves to hold the ring in place and yet permits it to move or yield slightly so that it may be drawn inwardly by the spring in 85 the metal so as to embrace the globe entirely around instead of at isolated points.

What I claim is:

1. In a shade or globe holder, an annular flange, a ring-like wire shade retaining element having a U shaped projection adjacent its middle portion, a slot formed in said annular flange through which said projection is adapted to extend, said slot being provided with a central restricted portion 90 adapted to be positioned to retain said projection in engagement with said flange, said ring-like element having its ends offset to form operating handles, and a second and elongated slot formed in said annular flange 95 through which said handles pass to the outside of the flange.

2. In a shade or globe holder, an annular flange, a ring-like wire shade retaining element having a U shaped projection adjacent 105 its middle portion, a slot formed in said annular flange through which said projection is adapted to extend, said slot being provided with a central restricted portion adapted to be positioned to retain said pro- 110

2
jection in engagement with said flange, said ring-like element having its ends overlapping and offset to form operating handles, and a second and elongated slot formed in said annular flange through which said handles pass to the outside of the flange, said second slot having a laterally enlarged cen-

tral portion and narrowed offset end portions.

WILLIAM C. HOMAN.
